UNITED STATES PATENT OFFICE.

JOSEPH ALOIS HROMADKO, OF NEW YORK, N. Y., ASSIGNOR TO THE MOTOR RADIATOR & MANUFACTURING CORPORATION, A CORPORATION OF DELAWARE.

RADIATOR.

1,413,163.

Specification of Letters Patent. Patented Apr. 18, 1922.

Application filed March 7, 1918. Serial No. 220,992.

To all whom it may concern:

Be it known that I, JOSEPH ALOIS HROMADKO, a citizen of the United States of America, residing in the borough and county

5 of Queens, city and State of New York, have invented a new and useful Radiator; and I do hereby declare the following to be a full, clear, and exact description of the same.

These improvements relate, especially, to 10 radiators which are principally made up of metallic plates or sheets, and the objects of the invention are, (1) to provide a form which is cheaply and quickly made, from units each of which is also cheaply and 15 quickly made; (2) to provide a form which may easily and quickly be repaired; (3) to provide a radiator which gives a maximum cooling area; other objects, as well as the advantages resulting from the invention, 20 will be spoken of hereinafter.

Referring to the accompanying drawings, Fig. 1 is a plan view of a fragment of sheet or plate metal, having frusto-conical projections, enlargements, or cups at opposite 25 faces thereof, and useful in making the preferred form of my radiator; Fig. 2 is a plan view, showing the water-passages between several sections of a radiator made according to my invention; Fig. 3 is a front elevation of the construction of Fig. 2, showing the air-passages or compartments; Fig. 4 is a section on the line 4—4, Fig. 1 through the aforesaid radiator, to show the interconnection, by openings, of the several 30 35 water-passages; Fig. 5 is a section, on the line 5—5, Fig. 1 through the aforesaid radiator; Fig. 6 is a like detail of a radiator-section where the several passages are interconnected by openings; and Fig. 7 is a fragmental front elevation of a radiator according 40 45 to my invention.

My new radiator may have any desired number of sections. When there are a plurality of sections, they should be arranged in succession and side by side, as shown in the drawings.

A radiator-section according to this invention, is in the form of a casing having sides made of metallic plates or sheets, said 50 sides preferably being parallel, the casing having a comparatively-long chamber narrow in one direction and wide in the direction at right angles thereto, which, in the preferred form of my invention, serves as a 55 passage for air to be utilized in cooling the radiator.

In the manufacture of a radiator-section, I preferably employ sheet or plate metal which may easily be bent to form the casing or chamber.

Referring to Fig. 1, A indicates a part of such a plate or sheet, of a material—for instance, a bronze composition—permitting it to be readily passed between rollers, or otherwise manipulated, to provide the sheet or plate with frusto-conical projections, pockets, or cups at both sides thereof. The projections or cups, C, from one side of a sheet or plate are shown as arranged in rows and relatively staggered, while the 70 projections or cups, D, from the other side of the sheet, are also shown as arranged in rows and also relatively staggered. Projections D are shown as being smaller than projections C.

The formation of projections from and at both sides of the sheet, may be assured, as is well known, merely by passing the sheet between rollers having the surfaces thereof toothed or otherwise formed to provide the two series of projections, C and D. Of course, a plate A may be of any desired length or width, these dimensions depending upon the size of the radiator-section.

In order to make a radiator-section, a plate or sheet (having projections at both sides) may be folded to have parallel side-plates, B and B', and with projections C in contact one with another—as shown, enlarged, in Fig. 6. Because the projections C are inside of the radiator-section, I have hereinafter designated those projections as inside projections. As a result of the bringing of the side-plates B and B' together, the radiator-section has (in the instance illustrated) a long and wide, and a comparatively narrow chamber, the walls of which are strengthened and are spaced apart, at intervals, by contacting or engaged projections C and C. The double bosses, thus formed by the contacting projections C, C are disposed in the path of the air currents which are caused to flow through the sections of the radiator when the car, aeroplane or other vehicle wherein the radiator is installed is in motion; and since the bosses are spaced apart by their staggered arrangement the air will be free to circulate entirely around the bosses which thus provide a greatly-increased cooling surface and enable 100 a correspondingly-increased cooling action to be obtained.

105 110

The chamber also has projections, D and D', extending outwardly from its two side-plates. In the case illustrated, this will result merely from folding or bending the 5 sheet, as before mentioned.

Preferably, each plate or wall of the radiator-section has a flange, a, running along one edge thereof, and also has a flange, a', along another edge. As shown in the drawings, 10 these flanges are along the front and rear edges of each section. The flanges may be formed by rolling or otherwise treating the sheet of metal at the time that the projections C and D are formed. The top and 15 bottom of the section are closed, by the parts H and H', the former of which is integral with the sides B and B' and is produced by the folding of the blank upon itself, while the part H' is formed by overlapping the 20 in-turned bottom edges of said sides.

Any desired number of radiator-sections may be connected, to form a radiator. In the drawings, I have shown a group of four sections, arranged side by side, with the 25 flange a of one section in contact with the like flange of the next section, while the flange a' of one section is in contact with the like flange of the next section. Contacting flanges are secured together, 30 throughout their length of contact. This is preferably done by soldering, which also assures a water-tight joint. A group of radiator sections as mentioned, has a plurality of compartments or chambers, as W, 35 X, Y and Z, and, alternating therewith, compartments or chambers, as x, y and z. It will be noted, as shown in Figs. 2, 4 and 5, that the outer (shown as smaller) projections, D, contact, within the compartments x, y and z, and hold the wall of one 40 section away from the wall of the next section.

As a result of the arrangements described and shown, I produce an exceedingly-strong 45 and simple radiator, of sheet metal, which has a number of compartments or chambers each of which is wide in one direction, so as to have great capacity, and is also narrow in another direction, whereby a maximum 50 number of sections may be included within a minimum space. In practical use, I prefer that the chambers W, X, Y and Z shall constitute air passages, while the chambers x, y and z shall constitute water passages. 55 Chambers x, y and z are sealed, as before stated, along their top and bottom edges only, and this leaves the water-passages open freely at both ends of the radiator to communicate with the usual headers. Chambers W, X, Y and Z are open at their front 60 and rear, as will be understood, to permit large quantities of air to sweep straight through them. Water, while within the water-passages x, y and z, is in the form of 65 thin sheets excepting at the points where

the projections C are located and, therefore, readily parts with its heat through contact with the walls of adjacent radiator-sections. Those walls are cooled by the air in the chambers W, X, Y and Z. 70 These projections C, as has been stated, extend into the air spaces or chambers and in that way form pockets into which the water flows, the air readily circulating freely around the pockets and readily cooling the 75 water therein.

It should be noted, therefore, that the water-contact and radiating space of a water-passage is increased, to some extent, by the 80 projections C and D, which also increase the surface with which cooling air comes into contact.

As shown in Figs. 4 and 6, the projections or pockets C may have their bottoms pierced, and, when two such projections are 85 brought in contact so as to have the openings of both in register, the material at the edge of one opening may be turned or flanged, as at B⁴ of Fig. 6, over the edge, B¹⁰, of the other opening, thus producing 90 a cross-passage B⁵, from one water-passage to the next. Referring to Fig. 4, it is seen that all of the water-passages may thus be interconnected by cross-passages, at a plurality of points. In consequence, water, 95 while passing through the radiator, will flow widthwise and lengthwise of each water-passage and from passage to passage, and simultaneously in two directions, at right angles to one another, increasing the quantity of water subjected to the cooling action of the air. 100

In the present application, I have illustrated and described and claimed only a specific form of my invention, the broader aspects of my invention being claimed in my prior granted Patent No. 1,376,882, issued 105 May 3, 1921.

What I claim is:—

1. In a radiator, a succession of sections 110 arranged side by side, each section comprising a pair of metallic plates which form the sides thereof, a plurality of projections extending inwardly from each of said plates and serving to space the adjacent plates 115 apart, a plurality of projections extending outwardly from each of said plates and serving to space apart adjacent sections, said sections being secured together along their side edges, whereby air passages and water 120 passages are formed side by side and in alternation, and said inwardly extending projections being formed with openings, the 125 openings in one plate being in register with the openings in the opposite plate, said openings engaging to form tubular connections from one water-passage to another, to enable water to pass through the radiator in independent streams at right angles to each other. 130

2. In a radiator, a succession of sections arranged side by side, each section comprising a pair of metallic plates which constitute the sides thereof, a plurality of projections extending inwardly from each of said plates and serving to space the adjacent plates apart, a plurality of projections extending outwardly from each of said plates and serving to space apart adjacent sections, 5 said sections being secured together along their side edges, whereby a plurality of water-passages are formed between said sections, said water-passages being narrow in one direction and comparatively wide in a 10 direction at right angles to said direction and also alternating with air-passages formed between the plates of said sections, and the said inwardly extending projections being formed with openings, the openings in one plate fitting into the registering 15 openings in the opposite plate, so as to form tubular connections from one water-passage to another, to enable water to pass through the radiator in independent streams at right 20 angles to each other.
3. In a radiator, a succession of sections arranged side by side and spaced apart to provide water passages between them, each section comprising a pair of parallel plates formed with a plurality of isolated projections 25 which extend inwardly therefrom to provide water pockets communicating with the water passages; the projections on the plates of each pair contacting immediately 30 with each other so as to space the plates apart and thereby provide an air passage between them, and the projections themselves being spaced from one another both horizontally and vertically to permit the air 35 to circulate entirely around them; the pairs of contacting projections having registering 40 openings to form cross-passages connecting the adjacent water passages.
4. In a radiator, a succession of sections arranged side by side and spaced apart to provide water passages between them, each section comprising a pair of parallel plates formed with a plurality of frusto-conical 45 projections which extend inwardly therefrom; the projections on the plates of each pair abutting directly against each other so as to space the plates apart and thereby provide an air passage between them, and having 50 registering openings to form cross-passages connecting the adjacent water passages.
5. A radiator section, embodying a pair of parallel plates provided upon their inner faces with a plurality of inwardly-extending projections which are of counterpart formation and are located directly opposite each other so as to abut against each other and thereby space the plates apart to produce an air passage between them; the adjacent projections of each plate being spaced from one another both laterally and longitudinally to permit the air to circulate entirely around them and being provided with central openings, the openings in each pair of abutting perforations being in register. 60
6. A radiator section, embodying a pair of parallel plates provided upon their inner faces with a plurality of inwardly-extending projections which are of counterpart formation and are located directly opposite each other so as to abut against each other and thereby space the plates apart to produce an air passage between them; the adjacent projections of each plate being disposed in staggered relation to permit the air to circulate entirely around them and being provided with central openings, the openings in each pair of abutting perforations being in register. 65
7. A radiator section, embodying a pair of parallel plates which are provided upon their inner faces with sets of abutting, inwardly projecting cups, whereby they are spaced apart to form between them a passage open from front to rear of said plates 70 and which are also provided upon their outer faces with outwardly projecting cups to space the adjacent sections apart when a plurality of them are arranged side by side and thereby provide passages between said sections which open from top to bottom thereof, the sets of abutting first-named cups being formed with communicating openings and being spaced from one another both laterally and longitudinally. 75
- In testimony whereof, I have signed my name to this specification in the presence of two subscribing witnesses.
